UNITED STATES PATENT OFFICE.

OSCAR B. BRANN, OF PORTLAND, MAINE.

AUTOMATIC STEAM-PRESSURE AND HEAT REGULATOR.

SPECIFICATION forming part of Letters Patent No. 363,275, dated May 17, 1887.

Application filed July 3, 1886. Serial No. 207,021. (No model.)

To all whom it may concern:

Be it known that I, OSCAR B. BRANN, residing at Portland, in the county of Cumberland and State of Maine, have invented certain new and useful Improvements in Automatic Steam-Pressure and Heat Regulators; and I do hereby declare that the following is a full, clear, and exact description of the invention, which will enable others skilled in the art to which it appertains to make and use the same.

The mechanical features of my invention are fully illustrated in the accompanying drawings, in which—

Figure 1 is a view in perspective of the invention with signal-bell attached; Fig. 2, a vertical section showing internal arrangement of the parts by which the steam-pressure and heat are regulated.

Similar letters of reference point out similar parts throughout the several views of the drawings.

My invention relates to an automatic steam and heat regulator and signal, which may be applied to any steam-boiler, hot-air chamber, and the like, wherein a uniform pressure of steam or uniform degree of heat is desired.

This invention is especially adapted for the use of dentists, and it has been designed as an improved attachment for any of the vulcanizers now in common use among dentists for vulcanizing the bases of artificial teeth, for the purpose of supplying a simple and efficient mechanical means whereby the steam-pressure may be kept uniform in the vulcanizers without requiring the operator to exercise constant care and attention over his work.

The invention consists of the combinations, arrangements, and adaptations of parts herein-after set out.

A in Fig. 1 is the top of a vulcanizer, steam-box, hot-air chamber, or other analogous device wherein the steam-pressure or heat is to be generated.

Rising perpendicularly above the part A is seen a cylindrical tube, C, within which is contained certain parts of the operating mechanism.

B is a nut which forms the coupling by which the cylinder C is attached to the part A.

D is a plug or plunger fitting the bore of the cylinder C. To each end of this plunger, by means of a screw, d, is attached a washer and

rubber packing to prevent leakage of steam or gas. The top of the upright cylinder C is covered with a screw-cap, G. Between the under side of the cap G and the head of the plunger D is confined a spiral spring, F. Near its center the upright cylinder C is provided with a right-angled cross-piece, E, which is a hollow tube. To the ends of the hollow cross-piece E are attached lengths of rubber tubing. One length extends to a gas-jet or other gas supply. The other length passes to a flame-chamber beneath the receptacle A. The plunger D at the point where the tube E crosses the upright C is grooved with a circular groove, d', which permits the free passage of gas through the tube E from the jet or supply to the flame-chamber.

The operation of the above-described parts is as follows: The cylinder C is first attached to the steam-box or vulcanizer A by means of the coupling-nut B, screwed to anyconvenient pipe or post thereon. Connection is then made with a gas-supply by means of a rubber tube, e, from one end of the cross-tube E. The rubber tube at the other end of E is passed to the heater under the steam-box or vulcanizer A. Gas is then turned on and passes through the tubes around the plunger D, through the groove d' at its upper part, into the flame-chamber under the generator A. When the gas is lighted, steam will be generated within the generator, which will create a pressure upon the lower end of plunger D and cause it to rise through the pipe C and coupling B. As the plunger D rises the spiral spring F will be compressed between its top and the cap G. At the same time the groove in the plunger D will be carried past the openings of the tube E, shutting off, in whole or in part, the flow of gas from the supply. Obviously, as soon as the gas-flow is diminished there will be less flame under the generator A, and consequently less steam-pressure within against the lower end of the plunger D.

For the purpose of obtaining a uniform steam-pressure and corresponding supply of gas the following manipulation is observed: If it is required to maintain a uniform pressure of fifty pounds, heat is applied, as above indicated. The plunger D is held hard down by screwing the cap G over the cylinder C and compressing the spring F until the de-

sired pressure is indicated. The nut G is then raised, releasing the spring F, and allowing the plunger D to rise and diminish the supply of gas until just enough gas will be fed under 5 the generator to hold the pressure at the required point. Thus by turning the screw-cap G on or off the end of the cylinder C the plunger D can be adapted to work at any desired pressure. Having once got the pressure regulated at any desired point, by means of the screw-cap, it will shut off at the same point whenever heat is applied to generate pressure.

In connection with my scheme for regulating steam-pressure in vulcanizers and the like, 15 I have devised a signal mechanism, whereby the operator, having once put the machine in operation, may leave it to perform its work while he busies himself with other occupations, paying no other attention to the machine than 20 to make a note of its signals. To accomplish this I make use of a gong attachment or signal, as follows: A gong, I, is attached to the pipe E by means of a standard, J, held in place by a set-screw, j. A bell-crank arm, K, is attached to the standard J by means of a screw-post, k, to which is fastened a spiral spring, k', to control the force of the hammer k², acting on the gong I. The gong I acts as a signal to the operator when the desired pressure is 25 reached, and is sounded in the following way: As the plunger D is raised by the pressure the spindle H also rises up and the ring a comes in contact with the short arm of the bell-hammer, causing that to rise up and carry the hammer 30 away from the gong I. At the same time the required pressure or temperature is reached 35 the short arm slides by a, letting the hammer strike the gong I.

The time of striking is regulated to the same 40 time the pressure is reached by raising or lowering the ring a on the spindle H.

The particular advantage of the gong is to enable the operator to know the time when the desired pressure or temperature is reached 45 when he may be engaged at a distance.

When he hears the gong, he can look at his watch and take the time, and when the heat

has been applied the length of time required he can go to the machine and shut off gas at the stop-cock in the supply-pipe. 50

When the pressure is relieved, the plunger D is forced downwardly by the spring F, which also carries down the ring a, until it slips by and beneath short arm k² of the bell-hammer. Then all is ready for further use, working as 55 before.

Having now described my invention, I claim—

1. In combination with the gas-supply pipes and steam-chamber, the cylinder C, a vertically-movable plunger, D, having the groove d', adapted to regulate the supply of gas, substantially as and for the purpose described. 60

2. In combination with the gas-supply pipes and the steam-chamber, the cylinder C, and a vertically-movable plunger, D, circularly grooved at d', regulating the supply of gas, and a spring applied to said plunger, whereby any desired pressure can be obtained for the steam, substantially as and for the purpose set forth. 70

3. In combination with the gas-supply pipes, the steam-chamber, the vertical plunger D, having the groove d', the spindle H, having a ring, a, spring F, and cap G, standard J, the gong I, and spring-actuated and striking arm K, 75 substantially as and for the purpose set forth.

4. In combination with the steam-chamber, the cylinder or tube C, and the hollow cross-piece E, connecting with said tube, the vertical plunger D, grooved at d', the spindle H, the 80 spring F, and cap G, substantially as and for the purpose set forth.

5. In combination with the tube or cylinder communicating with the steam-chamber, a plunger therein circularly grooved and provided with a spring, and means, as described, for actuating the gong and the signal mechanism, substantially as set forth, whereby the condition of the steam-pressure is automatically announced, substantially as described. 85
